UNITED STATES PATENT OFFICE.

WILLIAM RODERICK BARCLAY AND FRANK BYCROFT KEALL, OF LEICESTER, ENGLAND, ASSIGNORS TO UNITED SHOE MACHINERY CORPORATION, OF PATERSON, NEW JERSEY, A CORPORATION OF NEW JERSEY.

FINISHING MACHINE.

Application filed September 26, 1925, Serial No. 58,942, and in Great Britain October 22, 1924.

This invention relates to finishing machines and is illustrated as embodied in an automatic machine for setting the edges of the soles of boots and shoes of the type shown in United States Letters Patent No. 1,078,684, granted November 18, 1913, upon the application of Frank B. Keall, Joseph Gouldbourn and Arthur E. Jerram.

Prior to the operation of setting the edges of the soles of shoes by means of a heated, rapidly vibrating iron, a stain is usually applied to the margin of the sole, and this stain usually contains a small component of wax. It has been found that the action of the vibrating tool tends to produce a slightly undulating effect on the edge being finished, which in the higher grades of work is objectionable. Apparently this is due to small ridges of wax which are left on the edge at the ends of the strokes of the iron.

Accordingly, an object of the invention is to obviate the difficulty above mentioned. This we accomplish by providing an improved machine of the type referred to having mechanism for varying the character of the operation of the tool during different traversing movements.

In the illustrated arrangement, in accordance with a feature of the invention, the supply of power to the tool is interrupted prior to the last traversing movement so that the setting of the shoe is concluded by a mere wipe of the iron along the edge with the iron held in a stationary position and not vibrating.

To make this action effective, the vibrating iron should be positioned definitely with respect to its range of movement so that its edge will be in proper position for wiping the edge of the sole during the latter traverses of the machine. A feature of the invention relates to mechanism arranged to stop the iron at a definite point in its path of vibration.

Wherever power is supplied to the vibrating tool by means of a driving belt, the mere slackening of the belt may not be sufficient to stop the vibrations of the finishing tool because of the small amount of power required for its oscillation. In view of this,

another feature of the invention consists in means arranged to lift the driving belt out of contact with the highest portion of the tool driving pulley at the same time that the belt is slackened.

In machines of the kind referred to it has been usual to cause the edge setting iron to be moved away from the shoe and to stop the machine in a region along the forepart which is comparatively straight and which therefore renders easy the movement of the iron into engagement with the edge of the sole on the next shoe to be operated upon. The last traverse of the shoe past the iron was therefore not a complete traverse from one side of the shoe to the other and a portion, from a point along the forepart to the shank on one side, was not operated upon. In the machine illustrated as embodying the present invention, such stopping of the traverse is undesirable since if, during the last traverse when the iron is stationary and is acting to smooth or sleek the edge of the sole, the iron were removed before the end of the traverse an undesirable mark, such as a hump of wax, would be left on the edge of the sole at the point where the iron was removed. Another feature of the invention therefore relates to mechanism by means of which the iron is maintained in contact with the edge of the sole until the end of the traverse at the shank is reached. The illustrated machine provides mechanism associated with the mechanism for reversing the traverse of the shoe which is arranged to move the tool away from the shoe at the completion of a particular traverse thereof.

In view of this arrangement and the desirability of applying the tool to the work in this type of machine at a comparatively straight portion of the forepart of the shoe, still another feature of the invention relates to mechanism arranged to cause a partial traversing movement subsequent to the removal of the iron from the work so that a comparatively straight part of the forepart of the shoe is positioned opposite the iron when the machine stops. In the illustrated machine the release of the tool-controlling mechanism is rendered effective to stop the

machine at a predetermined point in the cycle of traversing movement, by a cam-operated lever interposed between parts which are attached to the control valve and the control lever, respectively.

These and other features of the invention will best be understood from the following description taken in connection with the accompanying drawings, in which,

10 Fig. 1 is a front elevation of the machine with a part of the frame broken away to show the internal construction;

15 Fig. 2 is a side elevation of a portion of the machine shown in Fig. 1, to a larger scale, with certain parts in section;

Fig. 3 is a plan view of the machine shown in Fig. 1 with the upper part removed;

Fig. 4 is a detail, in elevation, looking at the machine from the back side;

20 Fig. 5 is a detail in elevation of certain mechanism for operating the control which governs the flow of liquid to the main hydraulic cylinder and stops the machine; and

25 Fig. 6 is a fragmentary section on the line 6—6 of Fig. 2.

The illustrated machine is an edge setting machine having provision for relative traversing movement between a shoe and a rapidly vibrating edge setting tool, to transfer 30 the point of application of the tool around the edge of the sole of the shoe. In the illustrated machine the traversing movement is effected chiefly by moving the work support on the frame of the machine, the tool being 35 so supported that its position may be adjusted to compensate for variations in the contour and plane of the edge of the sole.

The work support comprises a laterally disposed U-shaped frame or jack 20 upon the 40 lower arm of which a toe rest 22 and a heel rest 24 are mounted. An adjustable clamp 26 is also provided to embrace the counter part of the shoe to position it in the jack and a toe clamp 28 is moved against the toe of the 45 shoe by a hand-operated lever 30 to hold the work, the tension of this clamp being adjustable by means of a hand wheel 32.

The jack and tool are moved relatively by 50 automatic mechanism to transfer the point of operation of the tool around the sole edge, and mechanism controlled by feelers bearing upon the sole edge and by feelers bearing upon the tread face of the sole near its edge, imparts the relative angular movements between the shoe and tool that are necessary 55 to insure that the acting face of the tool shall bear evenly upon every part of the sole edge upon which it operates.

The jack 20 is secured upon the upper end 60 of a vertical spindle 42 journaled in bearings at one end of a frame 44 of which the other end is pivotally carried at 46 (see Fig. 3) upon a second frame 48 that swings about a vertical spindle 50 supported in the machine frame. The two frames 44 and 48 in their

mean position are disposed approximately at right angles to each other so as to permit horizontal movements of the jack in any direction.

A lobed cam 52 fixed to the lower end of 70 the spindle 42 has a cam groove formed in it which engages two rollers 54, 54 which are supported in a manner hereinafter described. The cam and rollers so guide the jack during its movement that the sole edge of the shoe 75 on the jack moves past the tool in a path agreeing approximately in shape with the contour of the sole edge, or in a path that is the mean of a variety of contours of shoe soles; the relative traverse of the tool and sole edge being brought into exact agreement 80 with the contour of the shoe under operation by the horizontal and vertical movements which are imparted to the jack and tool respectively by the feeler mechanism. 85

The mechanism for driving the jack 20 comprises a slide 56 (Figs. 2 and 3) that is mounted to reciprocate in guideways 58 and 60 attached to or formed upon the machine frame. The slide 56 is coupled by a piston rod 62 to the piston 64 of a hydraulic cylinder 66 secured to the machine. Motion is transmitted from the slide 56 to the jack by means of two chains or other similar flexible members 68 and 70. The chain 68 is secured 90 to the slide 56 at one end and after passing around pulleys 72, 74 and 76 is attached at its other end at 78 to the far side of the cam 52. The chain 70 also secured to the slide, passes around pulleys 80, 82 (shown in Fig. 2 directly below the pulley 74), 84, 86, 88 as shown in Figs. 2 and 3, and is fastened to the cam at 90. To increase the motion derived from the slide 56 the pulleys 74 and 82 are mounted one above the other upon the slide 105 while the remaining pulleys except 84 are carried upon the machine frame. The pulley 84 is carried upon a lever 92 pivoted to the machine frame and is acted upon by a spring pressed rod 94 to keep the chains 68 and 70 110 under the necessary tension. If desired the chains instead of being attached to the cam 52 may be secured to a pulley of corresponding formation.

By the connections above described the jack 115 is oscillated from side to side by the reciprocation of the slide 56 and the direction of motion of the slide is reversed automatically by the following mechanism:—A reversing cam 96 (Fig. 1) journaled in the machine frame 120 below the jack spindle 42 is flexibly coupled to said spindle by a universally-jointed connecting shaft 98. The reversing cam 96 partakes of the turning movements of the jack and a high part of the cam is adapted to engage and operate a lever 100 pivoted on the machine frame. The lever 100 by way of adjustable connections presently to be described actuates the valve 102 (upper left side of Fig. 3) that controls the supply of 125

fluid to both sides of the piston 64 in the hydraulic cylinder 66 before mentioned.

The point of operation of the tool is transferred along the sole edge of the shoe, from 5 the shank on one side of the sole, around the toe portion, to the shank on the other side of the sole; the direction of motion of the jack being reversed when the tool reaches the shank. To adapt the machine for operation 10 upon shoes of different sizes and styles, the points at which reversal takes place are made adjustable, and as shoes of different styles vary in the relative lengths of the sole edge on the inner and outer sides of the sole, each of 15 the said points of reversal is made adjustable independently.

The adjustable connections between the reversing cam 96 and the valve of the hydraulic cylinder 66 comprise a spindle 104 the lower end of which is engaged by the lever 100, said spindle being movable vertically in the machine frame and coupled to one member 106 of a clutch of which the other member is formed upon the guide pulley 88 over 20 which, as aforesaid, the jack actuating chain 70 extends. A vertical rod bored to receive the upper end of the spindle 104 is coupled to the latter by means of a pin and slot connection which causes the rod and the spindle 104 to rotate in company but permits the spindle to be moved endwise independently of the rod to actuate the clutch 106. A sleeve in frictional engagement with the rod has slidingly keyed to it a hub from which two tappet arms 25 extend. These arms are adapted to engage with one or the other of two stop plates which are adjustably mounted in the frame of the machine. Connections are provided from the vertical rod which are arranged to rotate a horizontal shaft 108 (near center of Fig. 1 and upper center of Fig. 3) to which there is connected a crank 110 pivoted to one end of a connecting rod 112 the other end of which is arranged to operate the reversing valve 102. 30 The position of the stop plates with respect to the tappet arms may be adjusted by means of rock shafts provided with operating handles 116 and 118 (Fig. 1) which are disposed on the front of the machine in a convenient position for the operator.

During rotation of the jack 20 the reversing cam 96 is rotated with the jack until the high part of the cam engages the lever 100 and raises the spindle 104 to force the clutch members 55 106 into engagement. A rod actuated from this clutch now rotates with the pulley 88 until one of the tappet arms has come into engagement with one of the stop plates, after which continued rotation of the said vertical rod is effective to move the rock shaft 108 which, through the crank arm 110 and the connecting rod 112, operates the valve 102 of the cylinder to change the direction of flow of the fluid in the latter. The motion of the jack is 60 now reversed in direction until the reversing 65

cam operates by the connections above described to cause the other of the two tappet arms to engage the corresponding stop plate and thus restore to the jack its original direction of motion. The direction of motion 70 of the jack is thus reversed at each end of its stroke, the exact point of reversal depending upon the position into which the stop plates have been adjusted, it being noted that as each stop plate is adjustable independently of its 75 companion each end of the stroke of the jack may be varied independently.

As the tool operates along the sole edge of the shoe, it is always maintained in a position normal to the contour at the point of its engagement by a correcting mechanism, herein-after described, which angles the jack in a horizontal plane. In order to maintain the tool and shoe in this relation when that portion of the sole margin at the juncture of the 85 shank and forepart is reached, the jack must be turned through a considerable angle. Advantage is taken of this fact by making the high part of the cam 96 of such extent that it actuates the lever 100 and initiates the operation of the reversing mechanism during that period in which the tool is traversing the contour of the sole edge at the juncture of the shank and forepart. While the angle through which the jack must be turned, as the tool 90 traverses this portion of the sole edge, varies widely in shoes of different styles, yet this angle is of considerable extent in any ordinary shoe, and by making the high part of the cam of an extent which is the mean of that 95 required for operation on a great variety of shapes of shoes, the machine may be constructed so that it will operate satisfactorily on practically any style of shoe. It will be clear that in this manner the point at which 100 automatic reversal of the traverse takes place is determined or controlled by the shoe contour; and it will be evident also that while the reversing mechanism has its action initiated upon the arrival of the shoe and jack in pre-determined relation, such action is completed 105 thereafter when a definite linear traverse between the shoe margin and tool shall have occurred; the extent of this traverse being predetermined by the adjustment of the stops. 110

In operating upon shoes of the same size and style it will be understood that although the total length of travel of the point of operation of the tool is the same for a "right" shoe as for a "left" the points at which reversal of the direction of motion of the jack should take place are different for each shoe; the configuration of the sole edge of the "right" shoe differing only from that of the sole edge of the "left" shoe in that it is reversed laterally. 120

In order that, after the machine has operated upon say a "right" shoe of a given size and style, the points of reversal may be shifted for a "left" shoe of the same size 130

and style without necessitating independent re-adjustment of each of the stop plates, each stop plate in the construction herein described has two portions which are located at different levels so that for any given adjustment one portion only of each stop plate is in operative relation with a tappet arm. Provision is made for effecting a relative shift of the tappet arms and the stop plates so that either portion of the stop plate may be brought into operative relation with a tappet arm. It is for this purpose of obtaining a ready adjustment for "rights" and "lefts" that two tappet arms are provided and that the hub of the arms is slidingly keyed upon the sleeve on the vertical rod. The two portions of each stop plate being located at different levels, each tappet arm can be moved into operative relation with either of the said portions of the stop plate to which it appertains by the raising or lowering of the hub; and this operation may be effected by means of an operating handle 120 secured to a rockshaft upon which an eccentrically disposed pin is mounted which engages a groove in the hub.

In operating upon shoes that differ somewhat widely from the normal (for example shoes with pointed toes or shoes with square toes), it will be evident that if the speed of the jack actuating mechanism is maintained constant the edge setting tool will travel over different parts of the sole edge with different velocities. In order to maintain constant the rate of relative travel of the tool in relation to the sole edge of such shoes, mechanism is provided for varying the speed of the piston 64 in the hydraulic cylinder 66. This mechanism comprises a long conical valve 122 for regulating the speed of admission of the fluid to the cylinder and this valve is also arranged to start and stop the traversing movement. The valve is connected by a horizontal link 124, Figs. 3 and 5, to an upright lever 125 fixed upon a rockshaft 126 journaled in the machine frame, the rockshaft having fixed upon it another lever 128 (Fig. 5) adapted to engage a sliding collar 130 (Fig. 3) abutting against the central portion of a lever 132 that is pivoted upon a semi-tubular frame 134 rotatably mounted in the machine frame. One end of the lever 132 rests against a speed changing cam 136 formed upon the hub of the cam 52 so as to rotate in unison with the jack 20. The contour of the cam 136 is such that, as the jack is moved to present to the tool different parts of the sole edge of the shoe, the lever 132 is actuated by the cam 136 and moves the valve lever to open and close the conical valve 122 to varying extents and thus to alter the power supply and hence the speed of the jack so that the relative traverse of the tool and the sole edge is maintained approximately constant in speed at all parts of the sole edge.

It will be noted that due to the lobed construction of the cam 52 and the arrangement of the chains connecting it with the slide 56, the speed of the motion transmitted to the jack is modified, and this motion is preferably made the mean required for the traverse of a variety of shapes of shoes. It will be noted also that combined with this mechanism is the speed changing apparatus just described, comprising the cam 136 and the conical valve 122, which varies the velocity of motion of the entire driving mechanism; and it will be clear that the effect of one of these mechanisms is superposed upon or employed to modify that of the other.

The cam 136 is constructed with different parts having contours shaped in accordance with different shapes of shoes and the lever 132 may be shifted so as to engage any one of the different contours of the cam. To enable this to be done the frame 134, upon which the lever 132 is pivoted, is mounted upon a spindle 138 that is carried in the frame of the machine and the frame 134 is slidably coupled at its end to a bush 140 provided with a handle 142 by means of which the frame 134 may be turned so as to alter the position of the end of the lever 132 upon the surface of the cam 136. A friction device is provided to maintain the frame 134 and the bush 140 in the positions into which they are adjusted. The spindle 138 that supports the frame 134 upon which the lever 132 is pivoted is screwed at its end into the machine frame; and by turning a knurled head 144 secured to the spindle 138 the frame 134 and with it the lever 132 may be moved so as to shift the valve lever 125 and move the conical valve 122 in or out of its casing. This adjustment of the frame 134 accelerates or retards generally the speed of the jack actuating mechanism but it does not alter the relative proportions of the variations in speed that are imparted to it by the cam 136.

The mounting for the edge setting tool 148 (Fig. 1) comprises a tool holder 150 having a shank slidably positioned in a T-shaped piece 152, the upwardly extending stem of the piece 152 being fulcrumed in a projection 154 from a sleeve 156 (Fig. 2) that is rotatably mounted in a bearing frame 158. The bearing frame is connected by pivots 162 to two pairs of twin levers 164 and 166 (Fig. 1). One pair of levers 164 are pivoted directly upon a lever 168 fulcrumed in the frame at 170 while the other pair of levers 166 are connected to the lever 168 through a bell crank 172 pivoted at 174 to said lever. The other end of the bell crank 172 is connected with the frame of the machine by anchor link 176. By this construction the tool holder can be vibrated laterally about the vertical axis of the T-shaped piece 152; the sleeve 156 and toolholder 150 can be angled

about the common axis of the shank and the sleeve 156; while the sleeve 156, tool holder 150 and bearing frame 158, during their lateral and vertical movements in following the sole edge, are maintained horizontal by the action of the twin links 164 and 166. These links in conjunction with the bell crank 172 and link 176 constitute a parallel motion device supporting the bearing frame 158.

10 The edge setting tool 148 is vibrated rapidly about the vertical axis of the piece 152 by connections from a shaft 178 which may be oscillated by any suitable mechanism.

15 The tool 148 is pressed against the sole edge of the shoe by means of a spring 196: and by the co-operation of this spring with the cam 52 on the lower end of the spindle 42 of the jack 20 the point of operation of the tool is caused to travel along the sole edge during the movement of the jack. But it is necessary during the movement of the jack that there be angular movement in a horizontal plane between the jack and the tool to maintain always the acting face of the tool in proper engagement with the sole edge at every part of the contour thereof. Further, it is necessary also that the jack and tool be turned relatively about an axis that is normal to the acting face of the tool 25 owing to the fact that all parts of the sole do not lie in the same plane. These movements of adjustment between the jack and the tool are effected automatically by the correcting devices hereinafter described.

35 The correcting device for angling the jack in a horizontal plane in relation to the tool comprises a hydraulic cylinder 198 (Fig. 3), the piston rod of which is connected by a link to a jack correcting lever 200 pivoted at 202 to the machine frame. This lever supports the two rollers 54, 54 hereinbefore referred to as engaging the groove in the cam 52 on the lower end of the jack spindle. A valve 204 (Fig. 1) of the hydraulic cylinder 198 is of the rotary type and is controlled by two edge feelers (not shown) which under the action of suitable springs bear upon the sole edge, one on each side of the edge setting tool 148. These edge feelers are interconnected by means of a cross bar which is joined to the upper end of a shaft 206 the lower end of which is joined to the valve 204. When the tool is bearing evenly upon the sole edge, the valve 204 is maintained closed but when the feelers are moved relatively to one another by changes in the contour of the sole edge passing the tool, its movement is effective to cause a rotation of the shaft 206 and hence of the valve 204. The valve being thus actuated causes the piston of the cylinder 198 to be set in motion so that the jack correcting lever 200 is turned upon its pivot 202. The jack 20 being connected to the lever by the rollers 54, 54 and the cam 52 will also be swung about the pivot 202 of the

lever 200 as a center until the sole edge of the shoe on the jack is returned by such movement to the position in which the tool bears evenly upon it, by which time the edge feelers will likewise be restored by the movement 70 of the sole edge to their initial position and they will close the valve 204 and stop the motion of the piston and of the parts connected therewith.

75 The correcting device that effects a relative turning movement of jack and tool about an axis that is normal to the acting face of the tool, comprises a hydraulic cylinder 210 (Fig. 2) the piston of which is connected by a thrust rod 212 with an extension 214 from a collar that is secured to the projection 154 from the sleeve 156. A spring (not shown) connects the sleeve 156 and the frame 158 and opposes the thrust of the rod 212. A valve 218 (Fig. 1) that regulates the admission 85 of fluid to the cylinder 210 is controlled by two tread feelers 220 that bear upon the tread face of the sole of the shoe immediately adjacent to the sole edge. These feelers are connected by a cross bar which is coupled by 90 a shaft 222 with the rotary valve 218 of the cylinder 210. The action of this correcting device is similar to that first mentioned.

95 To move the tool into engagement with the sole edge or to remove it therefrom, a starting and stopping lever or controlling lever 230 is provided which is fixed upon a rock-shaft 232 journaled in the machine frame. The rock-shaft 232 has upon it an arm 234 inside the frame to which is pivotally linked 100 a plunger 236 into which extends a rod 238 free to turn within a bearing upon the frame lever 168. The spring 196, the function of which is to keep the tool pressed against the sole edge while the machine is in operation, 105 surrounds the rod 238 and abuts at its lower end against a collar supported by projections from a nut 242 working on a threaded portion of the rod 238 and at its upper end against an abutment 244 pivoted on the lever 110 168. A collar 246 secured to the upper end of the rod 238 operates to limit the movement of the rod in the abutment 244 under the influence of the spring 196. By this construction the tool can be moved yieldingly toward 115 the sole edge and removed positively therefrom. Preferably the plunger 236 works in a dash pot 248 which cushions the movement of the controlling lever 230 and the tool supporting lever 168 when the machine is 120 thrown automatically out of action.

125 A cam 250 (Fig. 5) on the rockshaft 232 is adapted to engage an arm extended from a lever 251 on the rockshaft 126 (Figs. 3 and 5) that is coupled to the conical valve 122 130 so that this valve may be shut until the controlling lever 230 has been moved sufficiently to bring the tool into engagement with the work, at which time the valve will be permitted to open by the disengagement of the 130

cam 250 from the arm aforesaid to start the movement of the jack to transfer the point of operation of the tool around the work.

A handle 262 pivoted to the free end of the controlling lever 230 is provided with a tooth 264 (Fig. 3) adapted to engage an aperture in the machine frame so as to hold the lever in the position which it occupies while the machine is running.

10 The machine comprises an automatic mechanism that stops its operation after a pre-determined number of traverses of the tool around the sole edge. And this number of traverses can be varied by an adjusting device. To this end a tappet piece 266 (Figs. 1 and 4) on the reciprocating rod 112 that forms part of the jack-reversing, valve-actuating mechanism is adapted to lift one end of a lever 268 pivoted upon the machine frame. This opens a valve 270 (Fig. 1) which operates a plunger 272 operatively connected to an arm 274 (Figs. 1 and 3) of a rocking frame 276 that turns upon a spindle supported in the machine frame. Another 20 arm 278 (Fig. 3) on the frame 276 carries a pawl 267 that engages a ratchet wheel 280 that has coupled to it an arm 282. This arm has a cam face that is brought by rotation of the ratchet wheel 280 into engagement with a spring-pressed plunger 284 mounted in the machine frame. The plunger 284 when moved endwise by the cam face of the arm 282 forces the tooth 264 on the handle 262 out of the aperture in the machine frame 30 thus releasing the controlling lever 230 and allowing the tool and its supporting device to fall away from the work. In the operation of this automatic mechanism the ratchet wheel 280 is moved by the connections from the tappet piece 266 at each reversal of the jack until the latter has made the number of movements for which the mechanism is set, when the cam arm 282 will release the controlling lever 230, and the tool will move 40 away from the work. Means including a rotatable stub shaft 290 are provided for adjustably determining the number of traverses of the jack past the tool. This release of the controlling lever 230 is not immediately effective (as later described) to stop the machine.

55 A pump 292 is provided which supplies fluid under the requisite pressure to the hydraulic cylinders of the machine and there is an air chamber 294 into which the fluid is pumped before passing to the hydraulic cylinders. Power is supplied to the machine through a shaft 296 on which is mounted a driving pulley 298 (Fig. 3).

60 Mechanism is provided which is arranged to interrupt the supply of power to the tool prior to the completion of the traversing movements. In this machine the stub shaft 290 which is rotated to determine the number of traverses of the jack past the tool has fixed

on it an arm 302 (Figs. 1 and 3) which is connected by a bar 303 to a block 304 slidingly mounted on a second bar 305. The position therefore of the block 304 on the bar 305 is varied as the number of traverses is varied. The bar 305 is pivotally connected at 306 to the starting and stopping or controlling lever 230. The bar 305 has formed at its right-hand end a notch 308 which, when the starting lever 230 is moved manually counterclockwise 75 into the position shown in Fig. 1 to start the machine, engages a block 309 carried on one arm 310 of a bell-crank lever 311 pivotally mounted on a vertical shaft 312 carried in the frame of the machine. A second arm 313 of the bell-crank lever is connected by a link 314 (Fig. 2) to one arm 315 of a lever pivotally mounted on a horizontal shaft 316 (Fig. 1) extending across the machine and fixed to the hub of this lever is a belt tightening-arm 317 carrying at its outer end a pulley 318 around which the belt 319 by which the edge setting iron is driven passes. The arrangement is such that when the starting lever 230 is moved into position to start the machine 80 the belt is tightened to drive the edge setting iron. At the end of each traverse of the shoe past the tool the shaft 290 of the counting mechanism is moved one step and therefore the block 304, which is slidingly mounted on the bar 305, is moved step-by-step along the bar and at the end of the last traverse but one is moved beneath a screw 320 carried in one arm 321 of a lever pivoted in the frame of the machine. The other arm 322 (Fig. 2) of 85 this lever has in it a screw 323 which is positioned in the path of a cam 324 carried on the slide 56 so that when the slide reaches one end of its traverse and the shoe is at the reversing point in its last traverse the other arm 321 of the lever is depressed carrying with it the screw 320 to engage the block 304 (Fig. 1) and move it and the right-hand end of the second bar 305 downwardly against the action of a spring plunger 326 so as to disengage the 90 notch 308 in the bar 305 from the block 309 in the bell-crank lever 311 and relieve the tension on the belt and stop the oscillation of the edge setting iron. The shoe is then traversed past the iron from one side to the other with the oscillations of the iron eliminated so that the sole edge is wiped round once by the non-vibrating iron to smooth off any waves which may be left by the vibrating iron.

95 At the same time that the belt is slackened 100 it is also desirable to lift the belt out of contact with the highest portion of its driving pulley 327 so as to prevent the iron from being driven by such contact after the belt is slackened and for this purpose the second arm 105 328 of the lever 315, to which the belt tightening arm 317 is fixed, is connected by a rearwardly extending link 329 to an arm 330 of a belt raising member 331 pivoted upon a horizontal shaft 332 carried in the frame of the 110

machine. The belt raising member 331 is in the form of a fork (Fig. 6) straddling the upper portion of the driving pulley 327 and having the upper surfaces of the fork arms curved to substantially the same radius as the radius of the pulley. The belt 319 is of such width that it projects over the edges of the pulley so that when the raising member 331 is swung upwardly as the belt is slackened it engages the belt at each side of the pulley and lifts it clear of the pulley. A stop (not shown) is provided to limit the upward movement of the raising member 331 so as to prevent the belt from being drawn against the lower portion of the pulley.

When the edge setting iron is stopped it is desirable that it shall be in the mid position of its oscillation and for this purpose the edge setting iron oscillating shaft 333 (Fig. 2), which is arranged to oscillate the vertical shaft 178 (Fig. 1), has fixed on it an eccentric 334 which is engaged by one arm 335 of a lever pivoted on the machine frame. The other arm 336 of the lever has formed on it a cam 337 which is engaged by a roller 338 on an arm 339 projecting upwardly from the belt raising member 331 so that when the belt raising member is swung upwardly to lift the belt from the pulley the arm 335 of the lever 335, 326 is swung on its pivot into the path of the eccentric 334 and as the high part of the eccentric comes round it is frictionally engaged by the arm and the oscillating shaft is stopped with the iron in its central position.

In machines of the kind referred to it has been usual to cause the edge setting iron to be moved away from the shoe and to stop the machine at a position along the forepart which is comparatively straight and which therefore renders easy the movement of the iron into engagement with the edge of the sole on the next shoe to be operated upon. The last traverse of the shoe past the iron was therefore not a complete traverse from one side of the shoe to the other inasmuch as a portion, from a position along the forepart to the shank on one side, was not operated upon. In the illustrated machine such stopping of the traverse is undesirable since if during the last traverse when the iron is stationary and is acting to smooth or sleek the edge of the sole the iron were removed before the end of the traverse an undesirable mark, such as a hump of wax, would be left on the edge of the sole at the point where the iron was removed. In the present construction, therefore, the iron is not removed from the edge of the sole until the end of the traverse at the shank is reached. In machines as heretofore constructed the iron has been removed by the action of a cam at a constant point in the traverse of the jack past the tool but in the present machine where the tool is removed at the end of the traverse such a mechanism is not altogether suitable

since the point at the end of the traverse varies with different sizes of shoes and also varies with right or left shoes and such a cam would require to be adjusted both for different sizes of shoes and for rights and lefts. In 70 the present construction the removal of the iron from the shoe is controlled by the mechanism which reverses the traverse of the shoe at each end of the traverse so that the wiping or sleeking action during the last traverse is 75 with different sizes of shoes or lefts and rights always carried right to the end of the traverse. The mechanism for removing the iron from the work at the end of the traverse comprises the cam plate 266 (Fig. 4) which is, 80 as previously described, fixed to the connecting rod 112 between the valve which controls the traverse of the jack and the reversing mechanism. This cam plate, as the connecting rod is moved endwise, at the end of the traverse, lifts the arm 268 to engage the plunger of the valve 270 controlling the hydraulic plunger 272 (Fig. 1) which operates upon the arm of the rocking frame of the 85 automatic counting and stopping mechanism 90 which releases the control lever 230 to move the tool away from the work. At the end of each complete traverse around the edge of the sole and back the valve 270 is opened to cause the plunger to act upon the arm and rotate the 95 rocking frame 276 one step until at the end of the last traverse the starting handle 230 is automatically released and the iron withdrawn from the work.

After the iron has been withdrawn the 100 jack is traversed back some distance to position a comparatively straight portion of the forepart opposite the iron. For this purpose the slide 56 which traverses the jack has formed on it a cam 345 (Figs. 3 and 5) which 105 acts upon a bell-crank lever 346, held against the cam by a spring 347, said lever 346 acting to swing a vertically disposed lever 348 pivoted on the lever 251 on the rockshaft 126. The lever 348 has an arm 350 which has its 110 lower edge and one side beveled. During the operation of the machine the lever 348 is 115 swung idly but after the starting lever 230 has been released, throwing cam 250 clockwise (which in the prior arrangements would 120 act to stop the machine), the lower beveled end of the arm 350 is (by reversal of the slide 56 on continued movement of the jack and on 125 consequent movement of the cam 345 away from under the lever 346) in due time wedged by a spring 351 into a clearance space between the cam 250 on the starting lever rockshaft 130 125 and the lever 251 which is connected to the valve 122 which causes the starting and stopping of the machine so that the cam 250 and the arm 251 are then, by the arm 350, wedged apart to close this valve and stop the machine. The angular position of the jack after it has stopped is controlled by mechanism similar to that shown in Letters Patent of the United 130

States No. 1,472,071, granted Oct. 30, 1923, upon the application of Frank B. Keall.

Having described the invention, what we claim as new and desire to secure by Letters Patent of the United States is:

1. A machine comprising mechanism for causing a plurality of relative traversing movements between a shoe treating tool and a shoe support to cause the tool to treat the same area of a shoe on the support more than once, means for operating the tool during a traversing movement, and means for controlling the character of the operation of the tool constructed and arranged to operate the tool in one fashion during one traversing movement and in a different way during another different traversing movement.
2. A machine in which a shoe treating tool is caused to operate along the contour of a shoe comprising means for causing said tool to traverse said contour a plurality of times, and means for varying the action of the tool upon the shoe during the different operations around the contour constructed and arranged to produce a different action of the tool during one traverse from that during a succeeding traverse.
3. A machine in which relative traversing movement is caused between a vibrating shoe treating tool and a shoe support comprising mechanism for causing in a cycle a plurality of relative traversing movements between the vibrating tool and a shoe carried by said support, and means constructed and arranged to operate automatically during the cycle for interrupting the vibration of the tool between the several traversing movements.
4. A machine comprising mechanism for causing a plurality of relative traversing movements between a shoe treating tool and a shoe support to cause the tool to treat the same area of a shoe on the support more than once, means for vibrating the tool during one traversing movement, and means for holding the tool in a fixed position with respect to its axis of vibration during another different traversing movement.
5. In a machine of the class described, the combination of a shoe support, a shoe treating tool, driving means for said tool, driving mechanism for producing relative movement of said support and tool to transfer the point of operation of the tool along a shoe carried by said shoe support, means for controlling the application of power to said tool, mechanism for automatically stopping said relative movement, and means connected to said automatic stopping means constructed and arranged to interrupt the supply of power to said tool.
6. In a machine of the class described, the combination of a shoe support, a shoe treating tool, means for driving said tool, means for moving said support to transfer the point of operation of the tool along a shoe carried by
7. In a machine of the class described, the combination of a shoe support, a shoe treating tool, means for driving said tool, means for moving said support to transfer the point of operation of the tool along a shoe carried by the shoe support, manually controlled mechanism for predetermining the number of traversing movements of the shoe support, and means operatively connected with said mechanism for interrupting the supply of power to the tool prior to the commencement of the last traversing movement.
8. In a machine of the class described, the combination of a shoe support, a shoe treating tool, means for driving said tool, driving mechanism for producing relative movement of said support and tool to transfer the point of operation of the tool along a shoe carried by said shoe support, and means for bringing the tool and shoe into operative relation constructed and arranged to control the supply of power to the tool.
9. In a machine of the class described, the combination of a shoe support, a shoe treating tool, means for driving said tool, driving mechanism for producing relative movement of said support and tool to transfer the point of operation of the tool over a shoe carried by said shoe support, and manually operable means for bringing the tool and shoe into operative relation constructed and arranged to supply power to the tool as the latter is brought into operative relation with the work.
10. In a machine of the class described, the combination of a shoe support, a shoe treating tool, means for driving said tool, driving mechanism for producing relative movement of said support and tool to transfer the point of operation of the tool over a shoe carried by said shoe support, means for supplying power to the tool comprising a belt, and manually operable means for bringing the tool into operative engagement with the shoe constructed and arranged automatically to render the belt drive of the tool effective.
11. In a machine of the class described, the combination of a shoe support, a shoe treating tool, means for driving said tool, driving mechanism for producing relative movement of said support and tool to transfer the point of operation of the tool over a shoe carried by said shoe support, means for supplying power to the tool comprising a belt, and

mechanism for bringing the tool into operative engagement with the shoe constructed and arranged automatically to render the belt drive of the tool effective.

5 12. In a machine for operating on boots and shoes embodying an oscillating tool adapted to be stopped at a particular point in its cycle of operation, means for driving said tool comprising a drive pulley, a belt 10 connecting said pulley with said tool, and means for tightening said belt, and means connected with said means constructed and arranged to lift the belt away from the drive pulley when the tightening means is released.

15 13. In a machine for operating on boots and shoes embodying an oscillating tool adapted to be stopped at a particular point in its cycle of operation, mechanism for driving said tool comprising a drive pulley, a belt 20 connecting said pulley with said tool, and manually operable means for tightening said belt, and means connected with said mechanism constructed and arranged to lift the belt away from the drive pulley when the tightening means is released.

25 14. In a machine in which a tool is caused to operate along a contour of a shoe, the combination of a shoe support, a tool, driving means for said tool arranged to move the tool 30 in a cycle, mechanism for producing relative movement of said support and tool to transfer the point of operation of the tool over the shoe, said mechanism being constructed and arranged to cause a plurality of relative traversing movements, means for automatically 35 interrupting the traversing movements between the shoe and the tool, and means interconnected therewith constructed and arranged to stop the tool at a predetermined 40 point in its cycle of movement.

45 15. In a machine in which a plurality of relative traversing movements are produced between a shoe support and a tool, means for driving said tool in a cycle comprising a belt, and automatic mechanism arranged to become effective at a predetermined point in the traversing movements between the work and the tool constructed and arranged to separate the tool-driving belt from its source of power 50 and to stop the operation of the tool at a predetermined point in its cycle of movement.

55 16. In a shoe treating machine, a treating tool mounted to oscillate about an axis in substantially continuous contact with a shoe on a shoe support, means for driving said tool to oscillate it in a cycle, and mechanism constructed and arranged positively to stop the oscillation of the tool in a predetermined angular relation to its axis.

60 17. In a machine for setting the edge of the sole of a shoe, a shoe support, a tool, means for vibrating said tool, means for producing a plurality of relative traversing movements between the shoe support and the tool, and automatic mechanism constructed and ar-

ranged to interrupt the vibration of the tool prior to the last traversing movement so that the tool is held vibrationless in contact with the work during the last traversing movement.

65 18. In a machine of the character described, a shoe support, a power-operated tool, means for causing a plurality of relative traversing movements between the shoe support and the tool to transfer the point of operation of the 70 tool along the contour of a shoe carried by the shoe support, means responsive to said traversing movement constructed and arranged to interrupt the supply of power to the tool, and means to predetermine the number of 75 relative traversing movements between the shoe support and the tool constructed and arranged to render said interrupting means effective at the completion of a traversing movement prior to the last.

80 19. In a machine for operating upon shoes, in combination, a shoe support, a tool, means for holding said tool in operative engagement with a shoe carried by said shoe support, and means for producing relative traversing 85 movements of the tool and the shoe support to transfer the point of operation of the tool along the contour of a shoe carried by the shoe support comprising means responsive to said traversing movements for reversing the traversing movements, said reversing mechanism being constructed and arranged to control the mechanism which holds the tool in engagement with the shoe in such manner that an interruption of the engagement between 90 the tool and the shoe is made effective at the end of a traversing movement.

95 20. In a machine of the character described, a shoe support, a tool, means for moving said tool into and out of operative engagement 100 with a shoe carried by said shoe support, means for causing a plurality of relative traversing movements between the shoe support and the tool, means for stopping the relative traversing movement, and means responsive to the relative position of the tool and the support constructed and arranged to interconnect the mechanism for moving the tool into and out of engagement with the work with mechanism for stopping the machine in such manner that the release of said tool controlling mechanism is effective to stop the machine at a predetermined point in the cycle of traversing movement.

105 21. In a machine of the class described, the combination of a shoe support, a tool, driving mechanism arranged to produce a plurality of relative traversing movements between said shoe support and tool to transfer the point of operation of the tool along a 110 shoe carried by the shoe support, means for reversing said driving mechanism to produce a reversal of the relative traversing movement, means for holding the tool and the shoe in operative engagement, and mecha- 115 120 125

nism responsive to the operation of said reversing mechanism constructed and arranged to effect an interruption of the engagement between the tool and the shoe support at the end of a traversing movement.

22. In a machine of the class described, the combination of a shoe support, a shoe treating tool, means for driving said tool, driving mechanism for producing relative movement of said support and tool to transfer the point of operation of the tool over a shoe carried by said shoe support, manually operable means for bringing the tool and shoe into operative relation constructed and arranged to supply power to the tool as the latter is brought into operative relation with the work, and automatic mechanism responsive to said relative
- 10
15

movement constructed and arranged to discontinue the supply of power to the tool.

23. In a shoe treating machine, means for producing a plurality of relative traversing movements between a shoe support and a tool, means for supplying power to drive said tool in a cycle, and automatic mechanism responsive to the relative traversing movements constructed and arranged to stop the supply of power for driving said tool so as to stop the cyclic movement of the tool at a predetermined point in the traversing movements.
